Attorney

UNITED STATES PATENT OFFICE.

VINCENT DOBBINS, OF NEW YORK, N. Y.

SLICING-MACHINE.

1,243,390.

Specification of Letters Patent. Patented Oct. 16, 1917.

Application filed March 26, 1917. Serial No. 157,466.

To all whom it may concern:

Be it known that I, VINCENT DOBBINS, a citizen of the United States, and resident of New York, in the county of New York and State of New York, have invented certain new and useful Improvements in Slicing-Machines, of which the following is a specification.

This invention relates to slicing machines and has more especial reference to an improved machine of the reciprocating cutter type.

The invention has for its dominant object to provide novel cutter operating means for the machine, the said means converting rotary motion into reciprocating motion which is imparted to the knife for operating the same.

Another object of the invention is to provide a movable carriage for supporting the material to be sliced by the machine and moving the same into engagement with the cutter, thus expediting the cutting operation and adding to the speed at which the machine can be operated, the carriage being moved simultaneously with the cutter and by the cutter operating means.

Among other aims and objects of the invention may be recited, the provision of a machine of the character mentioned with a view to compactness, and in which the number of parts are few, the construction simple, the cost of production small, and efficiency and operation high.

All of the foregoing together with additional advantageous details and arrangements of parts of the preferred embodiment of my invention will be clear from the specific description hereinafter contained, when read in connection with the accompanying drawings forming parts hereof wherein said embodiment of the invention is illustrated for the purpose of facilitating a full understanding of the present improvements.

In the drawings there is shown a side elevation of my improved machine with parts thereof broken away and shown in section.

Similar characters of reference are employed in the above described view to indicate corresponding parts.

Referring now more specifically to the said figure, there is provided a table or bed designated 1, which bed is provided with a plurality of parallel slots 2 and 3, the purpose of which will be subsequently apparent.

A plurality of rock arms 4 and 5 are pivotally mounted in bearings 6 secured to the under face of the bed 1 and have their upper extremities slotted, while the lower extremity of the former is slotted as at 7 and is provided with an apertured lug 8. Carriages 9 are arranged upon cross heads 10 slidably mounted in the slotted portions 6 of the rock arms 4 and 5 and are received in diagonally disposed guide ways formed by parallel arranged standards 11, it of course being understood that oppositely disposed pairs of the diagonally arranged standards 11 are employed in order that the opposite extremities of the cross heads with their respective carriages 9 may be received therein. A cutter 12 is pivotally connected at its opposite ends to the upper extremities of the rock arms 4 and 5.

A carriage 13 is slidably mounted upon the bed 1 and is engaged by a pivotal arm, which arm extends downward into engagement with the apertured lug 8 formed upon the lower extremity of the rock arm 4. An arm 15 is also pivotally connected to the apertured lug 8 upon the lower extremity of the rock arm 4 and extends into pivotal engagement with the apertured lower extremity of the remaining rock arm 5 and thus braces the lower extremities of each of the said rock arms, thereby insuring synchronous movement of the upper extremities of the same.

It is to be noted that the arm extends upwardly through the slot 2 formed in the bed 1, while the rock arms 4 and 5 project through the slots 3 therein.

A crank shaft 16 is extended transversely of the bed 1 and has its extremities mounted in suitable bearings, while the intermediate portion thereof is received in the slotted extremity 7 of the rock arm 4 whereby to impart oscillatory movement thereto upon rotation of the same. A balance wheel 17 is keyed to one extremity of the crank shaft 16 as at 18 and is provided with a handle 19 whereby the transmitting of rotary motion to the crank shaft will be facilitated.

In operation, upon rotation of the balance wheel 17 and the shaft 16, the upper extremities of the rock arms 4 and 5 will be oscillated and will cause reciprocatory movement of the cutter 12 by reason of its connection with the cross heads 10 as mounted in the inclined guide ways. Simultaneous with the reciprocation of the cutter 12 in one

direction, the carriage 13 will be moved in an opposite direction thereto and, obviously, will cause a shearing cut during the slicing of the material arranged thereon. By forming the upper extremities of the rock arms 4 of lengths greater than the lower extremities thereof, the speed at which the cutter 12 may be operated is materially increased and accords with the movement of the carriage 12 caused by its connection with the said lower extremities.

If desired, the cutter 12 may be braced during its travel or cutting operation by arranging the same between pairs of vertically disposed guide elements, the lower ends of which may be secured in any suitable manner to the bed or table 1.

As hereinbefore indicated, I do not wish to be understood as confining the invention 20 to the particular embodiment chosen for illustration herein, nor to the exact construction arrangement and adaptation of the parts shown and described, but I reserve the right to make any changes and alterations 25 that fairly fall within the spirit and scope of the invention.

I claim:

1. In a slicing machine, a bed, inclined guides arranged on the bed, carriages slidably engaged with said guides, a carriage movable on said bed, rock arms mounted on the bed and engaging said carriages, a cutter pivotally connected to the upper extremities of said rock arms, and means for imparting oscillatory motion to said rock arms.

2. In a slicing machine, a bed, inclined guides arranged on the bed, rock arms mounted on said bed and having their upper extremities formed of lengths greater 40 than the lower extremities thereof, carriages slidably engaged with the upper extremities of the rock arms and movable in the inclined guides, a cutter pivotally connected to the upper extremity of the rock arms, a carriage

movable on the bed, means for connecting the carriage to the lower end of one of the rock arms, and means for imparting oscillatory motion to said rock arms. 45

3. In a slicing machine, a bed, inclined guides arranged on said bed, rock arms mounted on said bed and having their upper extremities formed of lengths greater than the lower extremities thereof, cross heads slidably received by the upper extremities of the rock arms, carriages movably engaged with the inclined guides and carried upon the opposite ends of said cross heads, a cutter pivotally connected at its extremities to the cross heads, a carriage movable on the bed, means for connecting the carriage to the lower end of one of the rock arms, and means for imparting oscillatory motion to said rock arms. 50 55 60

4. In a slicing machine, a bed, inclined guides arranged on the bed, rock arms mounted on said bed and having their upper extremities formed of greater lengths than the lower extremities thereof, cross heads slidably received in the upper extremities of the rock arms, carriages arranged upon the opposite extremities of the cross arms and movably received in the inclined guide ways, a cutter having its extremity pivotally connected to said cross heads, a carriage movable on the bed, means for connecting the carriage to the lower end of one of the rock arms, a connecting rod engaged with the lower extremities of each of the rock arms, a crank shaft engaged with the lower extremity of one of the rock arms, and means 70 75 80 arranged on said crank shaft for facilitating rotation thereof.

In testimony whereof, I affix my signature hereto.

VINCENT DOBBINS.

Witnessed by—

JAMES J. CORBETT.
